UNITED STATES PATENT OFFICE

LOUIS SCHER, OF CLEVELAND, OHIO, ASSIGNOR TO THE TICKET ISSUING MACHINE COMPANY, OF CLEVELAND, OHIO, A CORPORATION OF OHIO

TICKET DELIVERY MECHANISM

Application filed November 20, 1930. Serial No. 496,938.

The invention relates to machines utilized for delivering or issuing and registering one or more tickets of one or more classes either simultaneously or selectively, and the present invention is an improvement upon the construction shown in the Louis Scher Patent No. 1,750,196, dated March 11, 1930, for ticket-delivery mechanism.

The particular class or type of ticket delivery mechanism to which the present invention and Patent No. 1,750,196 relate is characterized by the fact that the tickets are issued by and during the operation of the mechanism to restore its parts to an "initial" position after those parts have been actuated to move the same to an "operating" position as a result of a movement of any ticket key by an operator.

Ticket-delivery mechanism which is operated by and during the restoring movement of its parts to an initial position does not require its parts to be manufactured or constructed to close limits; does not require accurate clearances to be observed during assembly; and is not subject to inaccurate operation due to wear and continued use of the mechanism.

The accurate operation of ticket delivery mechanism of this class is only dependent upon the accurate relative location of a number of cams with respect to one another on a single master cam shaft, which cams control the entire operation of the ticket delivery mechanism.

Moreover, if a plurality of associated ticket keys are accidentally moved simultaneously, the mechanism will deliver a number of tickets corresponding to the key of the smallest denomination moved, so that the accidental simultaneous movement of a plurality of ticket keys can never cause a mistaken issuance of a larger number of tickets than desired.

The machine may, however, issue a smaller number of tickets than desired due to such accidental improper operation, but such a mistake can readily be corrected by a second operation of the machine to deliver sufficient tickets to make up for the mistaken smaller number of tickets previously issued by accident.

dental improper movement of a plurality of ticket keys.

The ticket delivery mechanism shown in Patent No. 1,750,196 is released from a locked "initial" position by manually operating a ticket key, after which the mechanism is driven by a continuously rotating motor driven shaft to move the parts to an "operating" position and to restore the parts to the initial position, at which "initial" position the continuously rotating shaft is operationally disconnected from any driving connection with the other parts of the mechanism, and the remaining parts of the mechanism come to rest until operation of the mechanism is again commenced by a later movement of a ticket key.

However, when the ticket delivery mechanism is being operated relatively infrequently to issue tickets, the noise or hum of a continuously rotating motor may annoy the operator, and the continued idle rotation of the motor may cause a useless expenditure or consumption of power.

It is therefore desirable to start and stop the motor for each ticket issuing operation, in cases when tickets are only to be infrequently issued.

On the other hand, there are times when it is necessary to issue successive groups of tickets as speedily as possible, for instance, when there is a long line of persons waiting at a ticket booth to purchase tickets. Under such circumstances, it is most desirable that the motor shaft be operating continuously so that a fraction of a second of time may be gained in performing each ticket issuing operation, and so that a continued making and breaking of switch contacts will not injure the contacts.

Accordingly, it is an object of the present invention to provide ticket delivery mechanism of the restoring movement type with a motor switch which may be manually operated to control continuous operation of the motor, or which is operated to start the motor by movement of the ticket key to supply power to the motor to carry out one particular ticket issuing operation only.

Moreover, it is a further object of the

present invention to provide one switch of the above character for the ticket delivery mechanism, whose operation may be selectively or simultaneously controlled by any 5 one of a plurality of identical ticket delivery sections which may constitute one installation driven by a single motor.

Tickets which are to be issued from a 10 ticket issuing machine are usually supplied in long continuous strips and it is most desirable to sever such strips at the proper place between successive tickets. For this reason, it is desirable to positively control the operation of the ticket delivery mechanism feed roll so that it will always stop 15 at a position which will enable the ticket strip to be sheared at the proper place between tickets.

Moreover, it is desirable to lock the ticket 20 feed roll against rotary movement in any direction when the same is at rest so that the feed roll will not be accidentally moved at a time when a ticket strip is being threaded in cooperative relation around the feed roll. 25 Feed rolls usually having counting or registering mechanism associated therewith which records all movement of the feed roll, so that an accidental movement of the feed roll may register the issuance of a ticket which has 30 not been actually issued, if the feed roll is not locked at all times excepting only when one or more tickets are being issued.

It is therefore a further object of the present invention to provide ticket delivery 35 mechanism with stop means for positively stopping rotation of the feed roll at a predetermined place so that the feed roll will not be overthrown by inertia of its own movement or movement of other parts, and so that 40 one or more tickets fed by the feed roll from a continuous strip of tickets will be severed at the proper place only.

Moreover, it is a further object of the 45 present invention, to provide ticket delivery mechanism with means for positively locking the feed roll against movement at all times, excepting only when the feed roll is being operated to actually issue one or more tickets.

At times, the operator of a ticket delivery 50 machine may accidentally continue to keep a key depressed during a ticket delivery operation, which will cause a successive issuance of a similar number of tickets unless a signal is given to the operator of the fact that 55 the ticket key is being pushed down.

It is therefore an object of the present invention to provide ticket delivery mechanism with means for positively raising every ticket key after each depression of the same, so that 60 the operator will be given a signal of the fact that the key is being pushed down, or so that the mechanism will not continue to operate in case some object is accidentally dropped on one of the ticket keys.

65 Ticket delivery machines are frequently

supplied with shears which are positively mechanically operated only in a shearing direction, and which depend upon spring or other such means for restoring the shear blade to an inoperative position. It frequently happens that the shear blade so operated may become tight or be jammed in its guide due to an accumulation of ticket cuttings, which may cause the entire machine to be jammed; and that the shear blade normally remains open.

It is therefore a further object of the present invention to overcome these difficulties in shear operation by providing positive mechanical means for operating the ticket shear in both directions so that the shear will only be operated at a time when a ticket strip has been fed to the shear for being cut off; and so that the shear remains closed excepting when carrying out the shearing operation.

It is a further object of the present invention to provide a locking device for simultaneously locking every ticket key of either one or a plurality of banks or ticket delivery sections in inoperative position so that an unauthorized person will be unable to operate the ticket delivery mechanism.

The ticket delivery mechanism shown in Patent No. 1,750,196 may accidentally be put out of order so as to prevent a restoring movement of its parts, if a ticket key of small denomination is depressed during the operation of the mechanism following the depression of a ticket key of large denomination.

It is therefore a further object of the present invention to provide means for preventing depression of a ticket key of small denomination during a ticket issuing operation actuated by depression of a key of large denomination in the same ticket delivery section.

The ticket delivery mechanism of the particular construction which comprises the present invention has a driving connection made or broken between the motor shaft and master cam shaft through the medium of a mutilated gear. It is most desirable that the mechanism parts be under absolute control at all times and that the various parts be restored to a fixed predetermined initial position after each ticket delivery operation.

It is therefore an object of the present invention to provide a mutilated gear construction in which when one tooth of the mutilated gear adjacent the mutilated portion thereof is disconnected from the driving gear, the drive end of the next tooth on the other side of the mutilated portion is in position to become engaged with the driving gear upon the slightest rotation of the mutilated gear shaft.

It is a further object of the present invention to provide ticket delivery mechanism of the restoring type in which every part thereof returns to an exact predetermined "initial"

position following a ticket delivery operation, and instantaneously remains at rest at such "initial" position until a ticket key has again been depressed.

And finally, it is an object of the present invention to provide a ticket delivery mechanism of the restoring type which has an extremely simple and economical design and construction, which is capable of accurate operation, which will not be affected by wear, and which will not easily get out of order.

These and other objects may be accomplished by the improved construction, a preferred embodiment of which is hereinafter described in detail, and shown in the drawings, in which:

Fig. 1 is a perspective view of the improved ticket delivery mechanism;

Fig. 2 is a vertical section taken on the line 2-2, Figs. 4 and 9 showing the improved ticket delivery mechanism;

Fig. 3 is a fragmentary view showing the shear operating cam;

Fig. 4 is a front elevation of the improved ticket delivery mechanism, parts of the casing being broken away to show one section of the mechanism in full lines;

Fig. 5 is a fragmentary view showing the improved mutilated gear construction;

Fig. 6 is a fragmentary front elevation of the improved master key and master key control cam construction;

Fig. 7 is a fragmentary plan section taken on the line 7-7, Fig. 6;

Fig. 8 is a fragmentary side elevation of the construction shown in Fig. 6;

Fig. 9 is a fragmentary rear elevation of the improved ticket delivery mechanism, parts of the casing being broken away to show one section of the mechanism in full lines;

Fig. 10 is a diagrammatic view of the improved control switch construction looking in the direction of the arrows 10-10, Fig. 4;

Fig. 11 is a plan section taken on the line 11-11, Fig. 2;

Fig. 12 is a fragmentary view of some of the parts shown in Fig. 11, showing the ticket delivery feed roll control segment in one position;

Fig. 13 is a plan section of the mechanism of one ticket delivery section taken on the line 13-13, Fig. 2;

Fig. 14 is a fragmentary elevation section of the ticket key and master key mechanism taken on the line 14-14, Figs. 2 and 11 and;

Fig. 15 is a fragmentary view of certain parts shown in Fig. 14 after a ticket key has been depressed to carry out a ticket issuing operation.

Similar numerals refer to similar parts throughout the drawings.

It may be explained in a preliminary way that the improved ticket delivery mechanism is preferably provided with a plurality of ticket delivery sections identical in construc-

tion primarily designed to issue or deliver different classes of tickets. All of the sections are preferably operated by a common motor so that the sections are ready to instantaneously deliver tickets from previously printed and prepared ticket strips.

Each section is equipped to keep total count of the number of tickets issued therefrom, and the number of tickets delivered is regulated by the particular ticket key depressed, which actuates a master key provided for each particular section.

A machine of this class is commonly required to rapidly deliver up to and including five tickets from each section, and the improved mechanism described herein is shown as having a ticket issuing capacity for each ticket issuing operation of five tickets, from each of three sections.

Thus, orchestra and balcony tickets for adults, and children's tickets may be respectively issued from the three ticket delivery sections marked A, B and C respectively in Fig. 1 of the drawings. However, any number of sections may conveniently constitute any installation merely by duplicating the mechanism constituting each section and providing for a common motor drive for all of the sections.

The improved ticket delivery mechanism preferably includes a casing formed by the removable combined partial front and top wall 16, rear wall 17, bottom wall 18, delivery plate or top wall 19 and end walls 20 and 20', while the individual ticket delivery sections A, B and C are separated by dividing walls 20a.

The ticket delivery sections A, B and C are all driven, after actuation by any ticket key, by a motor 21 preferably mounted on the side wall 20, and having its driving worm 22, meshing with the worm gear 23 mounted on the drive shaft 24, which extends through all of the associated sections of the mechanism. The drive shaft 24 rotates in a clockwise direction (Fig. 2) and has mounted thereon a drive gear 25 for each section.

It is understood that the mechanism constituting each of the sections A, B and C is identical, so that in describing mechanism provided for one section, it is understood that similar parts are provided for each ticket delivery section of the machine.

A drive pinion 26 meshing with the drive gear 25 is keyed to the shaft 27 which is mounted on the curved link or bracket 28, pivotally supported at 29 on the stub shaft 30 extending from the right dividing wall 20a of each section (Fig. 4).

The bracket 28 is normally urged to rotate in a clockwise direction (Fig. 2) about its pivotal mounting 29, by the coil spring 31, and movement of the bracket 28 in a clockwise direction is limited by the adjustable stop 32 which is threaded into the front cross

strip 33 of the mechanism. The stop 32 engages a lug 34 projecting from the bracket 28.

A ratchet gear 35 is also mounted on the shaft 27 and rotates in a counter-clockwise direction (Figs. 2 and 5) whenever the motor 21 is running.

A main cam shaft 36 is provided for each section, and is journaled at its end portions in the side or dividing walls 20, 20a or 20' of each section. Each cam shaft 36 is provided with a plurality of cams or gears, named in order of their respective positions from left to right (Figs. 4 and 13), as follows: cam shaft starting cam 37, master key raising cam 38, cam shaft stop cam 39, feed roll control segment operating cam 40, mutilated drive pinion 41, switch operating cam 42 and combined feed roll stop and shear operating cam 43.

Each section is provided with a keyboard comprising a plurality of keys 44, carrying designating numbers 1 to 5 respectively, to indicate the number of tickets which will be issued upon depression of one of the keys. Each key 44 is provided with a stem 45 which is slidably mounted in the bracket 46 secured by any suitable means to the section side walls 20 or 20a.

The lower end of each key stem 45 is provided with a notch 47 and a lateral shoulder 48 for purposes which will be hereinafter described. A side plate 49 is provided for each bracket 46 for retaining the key stems 45 against sidewise movement, and the side plate 49 is preferably provided with an aperture 50 adjacent each key stem, for the insertion of a friction washer 51, spring pressed at 52, for frictionally maintaining the key stems 45 at any position to which they may be moved.

The springs 52 are retained in their respective apertures 50 by a cover plate 53. The ends 54 of each of the key stems 45 are presented toward an actuating member 55, pivoted at 56, and provided with a cross bar 57 extending directly underneath the ends 54 of the key stems 45. The actuating member is provided with a finger 58 extending from the cross bar 57 in a direction opposite to the pivotal mounting 56.

The finger 58 ordinarily rests on the top end of the master key 59, preferably slidably mounted in a bracket 60, carried by the section side wall 20 or 20a, and the master key is normally maintained in any position to which it is moved by spring actuated friction means 61 carried by the bracket 60.

The lower end portion 59' of the master key 59, is normally located in the position above the cam 37, (Fig. 6) while a finger 62, provided with a laterally extending lug 63, projects forwardly from the lower end of the master key 59.

The lug 63 is located in a position to be engaged by the cam 38 for raising the master key, and to abut a similar lug 64 projecting

from the cam 39 when the master key is in raised position (Fig. 8).

The feed roll starting gear segment 65 is preferably integrally formed on one end of a bell crank lever 66, pivotally mounted at 67, on the shaft 68, and provided at its other end with a roller 69 maintained in contact with the cam 40 by the spring 70, which normally urges the bell crank 66 to rotate in a clockwise direction (Fig. 2).

An arc-shaped member 71 projects from the upper end of the bell crank lever 66 in a direction opposite to the gear segment 65, and is normally disposed at the side of the notches 47 formed in the lower ends of the ticket key stems 45, the outer end of the arc-shaped member 71 being offset at 72, for a purpose which will be later described.

The gear segment 65 meshes with a sleeve gear 73, rotatably mounted on the shaft 74, to which is keyed the feed roll 75. A ratchet wheel 76 is likewise keyed to the shaft 74, while its controlling pawl 77 is pivotally mounted at 78 on a mounting plate 79 fixed to the hub 80 of the gear 73. A ratchet wheel 81, cooperating with a spring pressed arm 82, is also fixed to the shaft 74 to prevent rotation of the shaft 74 in a counter-clockwise direction (Fig. 2).

A counter gear 83 is also fixed to the shaft 74 and drives the counter mechanism 84 through gearing 85. The counter mechanism 84 registers the number of tickets issued or delivered by any particular ticket issuing section.

The ticket feed roll 75 is provided with a plurality of radial projections 86 spaced circumferentially equidistant apart, and the projections 86 are adapted to engage openings or apertures 87, provided in a continuous ticket strip 88, which may be threaded through a guideway 89 opening adjacent the feed roll 75 and communicating with any suitable storage place for the continuous ticket strip 88, preferably located below the ticket delivery machine at 90 (Fig. 1).

The shaft 74, likewise has fixed thereto a stop ratchet wheel 91 which cooperates with the end 92, of a lever 93, pivotally mounted at 94, on the shaft 95, and having its other end 96 cooperating with the outer surface of the cam 43. The lever 93 is normally urged to rotate in a counter-clockwise direction (Fig. 2) by the spring 97. The lever 93 and cooperating ratchet wheel 91 normally maintain the shaft 74 against clockwise rotation (Fig. 2), excepting only when the lever end 92 is disengaged from the ratchet wheel 91 by the action of the outer cam surface of the cam 43 on the lever end 96.

A shear operating lever 98, pivotally mounted at 99, on the shaft 100, is provided at one end with a roller 101 engaging the internal cam surfaces 102 and 103 of the cam 43. A link 104 is pivotally connected to the other

end of the lever 98, and has its upper end pivotally connected at 105, to the shear blade 106, pivotally mounted at 107 on the shear mounting bracket 108. The shear blade 106 preferably operates between two guide plates 109 and 110, slotted at 111, for permitting the ticket strip, to be sheared, to pass between the guide plates and shear blade.

Ticket guide plates 112 preferably extend 10 downwardly from the top plate 19 to maintain the ticket strip 88 in cooperative engagement with the feed roll 75, while ticket guide fingers 113 and 114 project forwardly from the shear bracket 108, toward the feed roll 15 75, for guiding a ticket strip from the feed roll to the shear.

An exit opening 115, provided with a pivoted cover or door 116, is provided in the top plate 19, adjacent the shear, to provide an 20 exit from the shear, of tickets issued by, registered by, and sheared by the ticket issuing mechanism from a continuous ticket strip 88.

A finger 117 is mounted on the switch shaft 118 and cooperates with the cam 42 (Fig. 10). 25 The shaft 118 extends through all of the sections A, B and C of the ticket issuing machine, and is provided at its end adjacent the motor 21, with a lever 119, carrying a movable electrical contact member 120, adapted 30 to contact with the terminal contacts 121 and 122 of the wires 123 leading to and controlling the supply of electric power to the motor 21.

A switch lever 124, pivoted to the side case 35 member at 125, is provided with a lug 126 engaging the under surface of the lever 119, and is shown in full lines in Fig. 10 in "off" position. When the lever 124 is moved to "on" position, shown in dot-dash lines in Fig. 40 10, the movable contact member 120 makes contact between the terminal contacts 121 and 122 so that the motor will run continuously.

A locking shaft 127 is slidably mounted to extend through all the sections of the mechanism and is preferably provided at one end 45 with an operating knob 128. A collar 129 is mounted on the shaft 127 adjacent each actuating member 55. When the shaft 127 is moved so that the collar 129 is in the position 50 shown in dot-dash lines in Fig. 14, the collar 129 is directly beneath the cross bar 57 of the actuating member 55, so as to prevent any movement of the actuating member 55, to prevent any depression of any contact keys 55 44 and to lock the machine.

When the shaft 127 is moved so that the collar 129 is in the position shown in full lines, the same does not interfere with the 60 operation of the machine. Thus, locking means is provided for preventing unauthorized operation of the device.

Referring to Fig. 5, the mutilated gear 41 is provided with a cutout portion 41a which is only sufficient to cause a disengagement 65 between the gears 35 and 41 when those gears

are in the position shown, and the slightest rotation of the gear 41 will cause the first tooth below the mutilated portion 41a to be operatively engaged with the teeth of the gear 35.

It may happen that as the gear 41 is rotated, the high part of a tooth on the gear 41 will contact on a high part of a tooth of the gear 35. However, the flexible mounting of the bracket 28 permits the bracket to move 70 slightly to the left, against the tension of the spring 31, whereupon rotation of the driven gear 35 will cause the teeth of the gears 35 and 41 to be properly meshed, at which time the bracket 28 will spring back to the position 75 shown in the drawings, with the lug 34 contacting with the stop 32.

In order to assist in accomplishing a proper meshing engagement between the teeth of the gears 35 and 41, the teeth of the gear 41 80 just below the mutilated portion 41a thereof are formed on a partial spiral as indicated by the dot-dash line 41b.

Referring to Figs. 11, 12, 14 and 15, it is pointed out that the arc-shaped member 71 90 extends adjacent and to one side of the lower end of the key stems 45. When the arc-shaped member 71 moves to the position shown in Fig. 12 of the drawings, the notch 71a formed therein, between the member 71 and its offset portion 72, engages the lower end of the key stem 45 which is depressed as shown in Fig. 15, just above the notch 47 formed in the lower end of the key stem. In Fig. 12, the notch 71a is shown as engaging the second key stem, from left to right, which has been depressed to start the operation of the mechanism.

At the same time, the offset portion 72 extends within the notches 47 and directly beneath the ends of the stems 45 of all keys located at the left of the depressed key. As shown in Fig. 12, only one key stem 45 in Fig. 12 is prevented from being depressed by the offset 105 portion 72.

However, if the right (Fig. 12) "5-ticket" key 44 is depressed, the notch 71a will engage and be stopped by the lower end of the same 110 and the offset portion 72 will extend beneath the four remaining ticket keys to prevent depression thereof.

The various parts of the mechanism are shown in the drawings in a position which is termed herein as an "initial" position, at which position the parts always come to rest, instantaneously at least, following a ticket issuing operation, excepting only the position of parts shown in Figs. 12 and 15 which are termed herein an "operating" position.

The operation of the various parts of the mechanism, described above in detail, is as follows:

Let it be assumed that the operator desires to cause two tickets to be issued from a select-

ed section of the machine. The "No. 2" ticket key is depressed to the position shown in Fig. 15, and its end 54 engages the cross bar 57, of the actuating member 55, to move the member to the position shown in Fig. 15.

Meanwhile, the finger 58 engages the upper end of the master key 59, and moves the master key downward, so that the lugs 63 and 64 become disengaged to permit rotation of the shaft 36, and so that the lower end portion 59' of the master key engages and moves the cam 37 to partially rotate the shaft 36 in a clockwise direction.

The partial rotation of the shaft 36 causes the cam 42 (Fig. 10) to raise the finger 117 and rotate the switch shaft 118 in a counter-clockwise direction to move the movable contact member 120, in contact with the terminal contacts 121 and 122, to start the motor, causing a rotation of the drive shaft 24, shaft 27, and ratchet gear 35. Meanwhile, rotation of the shaft 36 causes the gears 35 and 41 to become meshed, so that motor driven rotation of the ratchet gear 35, continues to rotate the gear 41 in a clockwise direction.

As the shaft 36 rotates, the cam 40 presents its relieved surface to the roller 69, so that the spring 70 will rotate the bell crank 66 in a clockwise direction until the notch 71a of the arc-shaped member 71 engages the lower end of the depressed key stem 45, as shown in Fig. 12.

Meanwhile, the rack 65 rotates the gear 73, mounting plate 79, and controlling pawl 77 in a counter-clockwise direction (Fig. 2) freely on the shaft 74.

Meanwhile, the cam 43 moves the end 96 of the lever 93 upward, to cause its other end 92 to be disengaged from the ratchet wheel 91. At the same time, the internal cam surface 103 moves the lever 98 to raise the link 104, for raising the shear blade 106, to permit the tickets to be issued to pass between the shear blade 106 and its guide plates 109 and 110.

As the shaft 36 continues to rotate, the high surface of the cam 40 engages the roller 69, to rotate the bell crank 66 in a counter-clockwise direction, for restoring the same to its "initial" position, from the "operating" position to which it was swung by its spring 70.

As the bell crank 66 moves its rack 65 to the left (Fig. 2), the gear 73 and mounting plate 79 are rotated in a clockwise direction, whereupon the controlling pawl 77 engages its ratchet wheel 76, to rotate the ratchet wheel 76, and the shaft 74 to which it is keyed, in a clockwise direction.

Meanwhile, the feed roll 75 likewise keyed to the shaft 74, is rotated in a clockwise direction to move the ticket strip 88 engaged thereby through the shear until two tickets have passed beyond the shear blade. At the same time, the gearing 83-85 causes the

counter-mechanism 84 to register the fact that two tickets have been issued.

Just before the bell crank 66 has been restored to its initial position, because of engagement of the roller 69 with a high part of the cam 40, before the feed roll 75 ceases to rotate, the relieved outer cam surface of the cam 43 permits the spring 97 to move the lever 98 in a counter-clockwise direction, so that its end 92 engages the ratchet wheel 91 to prevent further clockwise rotation of the shaft 74. At this time, the cam surface 102 of the cam 43 moves the operating lever 98, to move the link 104 downward, so that the shear blade 106 severs the two tickets on the advanced end of the ticket strip, from the ticket strip 88.

Meanwhile, the two tickets which have been sheared, have issued out of the exit opening provided in the top plate 19 from beneath the pivoted door or cover 116 therefor, to a position where they may be picked up by the buyer.

At the time when the shear operates, the relieved portion of the cam 42 permits the lever 117 to drop downward to break the electrical connection between the contacts 121 and 122, so that the motor 21 will stop.

At the same time, the mutilated portion 41a of the gear 41 arrives at the position shown in Fig. 5, so that the driving connection between the gears 35 and 41 is disconnected.

Meanwhile, the cam 38 has engaged the lug 63 of the master key to positively raise the master key to the position shown in Fig. 14. The master key in turn raises the actuating member 55, and the depressed key 44 back to the position shown in Fig. 14. The key 44 and master key 59 will be maintained in such raised position by the spring pressed friction means 51 and 61, respectively.

After the master key has been raised by the cam 38, the lug 63 thereof projects in the path of the lug 64 of the cam 39, so as to prevent further rotation of the shaft 36 until the master key is again depressed by a succeeding operation of one of the key tickets by the operator.

In the operation of the mechanism above described, the motor 21 is started and stopped by each ticket issuing operation. However, when it is desired to rapidly issue successive tickets, the motor is run continuously by moving the switch lever 124 to the position shown in dot-dash lines in Fig. 10, when an electrical connection is made between the contacts 121 and 122 without regard to, or without being affected by, the operation of the cam 42 and finger 117. When the motor is operated continuously, the gear 35 rotates continuously, and picks up the mutilated gear 41 immediately after any ticket key has been depressed.

Since the operation of any ticket section is independent of every other ticket section, ex-

cepting for the common motor drive, the common locking means, and the common intermittent switch operating shaft; any section may be operated to issue tickets simultaneously with the operation of one or more other sections without affecting the operation of such other sections.

In event that two or more sections are being operated simultaneously when the switch lever 124 is in "off" position, the motor will continue to run until the last section actuated has issued its tickets, because the cam 42 of the last section operated will maintain the electrical connection between the contacts 121 and 122.

The cams 37, 38, 39 and master key 59 may be termed an escapement mechanism, because these cooperating parts start and stop rotation of the shaft 36, and at the same time positively raise the master key so as to require a ticket key to be depressed for performing a succeeding ticket issuing operation.

It is pointed out that the ticket keys and associated mechanism constitute manually-operable movement limiting means for the bell crank 66. The bell crank in being restored to its "initial" position, operates the ticket feed roll, and the amount of rotation imparted to the feed roll is dependent upon the amount of restoring movement imparted to the bell crank, which in turn is dependent upon its limit of movement from "initial" position to "operating" position which is controlled by the movement limiting ticket key depressed.

Accordingly, the present invention provides a ticket delivery mechanism of the restoring movement type, in which the mechanism parts are driven by a motor which may be either continuously operated, or which may be operated only for each ticket delivery operation.

Moreover, means is provided for positively preventing any overthrow of the ticket feed roll and for locking the feed roll against movement, excepting only when the feed roll is operated to feed a ticket strip.

The present invention also provides means for positively raising any depressed ticket key after each ticket issuing operation actuated by the ticket key; before any subsequent ticket key can be depressed, in the same section, to effect a subsequent ticket issuing operation.

Moreover, the ticket shear is positively mechanically moved in both directions so that the shear cannot become jammed to clog the ticket strip in its guideways, and so that the shear is normally closed.

Moreover, an effective locking device is provided for simultaneously locking all of the ticket keys in inoperative position.

And finally, the present invention provides means for preventing a small ticket key from being depressed during the operation of the

mechanism actuated by depression of a larger ticket key.

On the other hand, if, during the operation of the mechanism due to the depression of a ticket key, a larger ticket key is depressed, 70 it will have no effect upon the ticket issuing operation.

In the case where two or more ticket keys are depressed simultaneously, the mechanism will issue tickets corresponding to the smallest ticket key depressed, so as to avoid the occurrence of any errors in the operation of the device.

I claim:

1. In a ticket delivery machine, ticket issuing and severing mechanism, actuating means for said mechanism, manually-operable movement limiting means for said actuating means, an associated master key controlled by said limiting means adapted to start and stop said actuating means, means for driving said actuating means, and means for operating said driving means continuously or for operating said driving means by operation of the movement limiting means. 80

2. In a ticket delivery machine, ticket issuing and severing mechanism, actuating means for said mechanism, manually-operable movement limiting means for said actuating means, an associated master key controlled by 95 said limiting means adapted to start and stop said actuating means, and means for locking the ticket issuing mechanism in inoperative position except when the ticket issuing mechanism is being operated by the actuating 100 means.

3. In a ticket delivery machine, ticket issuing and severing mechanism, actuating means for said mechanism, manually-operable movement limiting means for said actuating means, an associated master key controlled by 105 said limiting means adapted to start and stop said actuating means, and said actuating means including means for moving the master key and its controlling movement limiting means to an inoperative position after each ticket issuing operation. 110

4. In a ticket delivery machine, ticket issuing and severing mechanism, actuating means for said mechanism, manually-operable movement limiting keys for said actuating means, an associated master key controlled by 115 said limiting keys, adapted to start and stop said actuating means, and means carried by the actuating means for rendering certain keys inoperative to control the master key after one key has been operated to start the actuating means.

5. In a ticket delivery machine, ticket issuing and severing mechanism, actuating means for said mechanism, manually-operable movement limiting means for said actuating means, an associated master key controlled by 125 said limiting means, said actuating means including an intermittently driv- 130

en member and an escapement actuated by the master key to start and stop the operation of the actuating means, and said escapement including means for raising the master key 5 to an inoperative position.

6. In a ticket delivery machine, a plurality of sections each including ticket issuing and severing mechanism, individual actuating means for each mechanism, a set of manually-operable movement limiting keys for the actuating means of each section, an associated master key for each section controlled by its respective set of movement limiting keys, a common driving device for all of said actuating means, means for operating said driving means continuously or for operating said driving means by operation of any of the movement limiting keys, and means for locking all of said limiting keys in inoperative 20 position.

7. In a ticket delivery machine, ticket issuing and severing mechanism, actuating means for said mechanism, manually-operable movement limiting means for said actuating means, an associated master key controlled by said limiting means, driving means for the actuating means, and said actuating means including an escapement actuated by the master key to start and stop the operation 25 of the actuating means, an intermittently driven gear, means for operating the driving means to drive the gear, means for operating the severing mechanism, and means for locking the issuing mechanism in inoperative position except when the ticket issuing means is being operated by the actuating 30 means.

8. In a ticket delivery machine, ticket issuing and severing mechanism, actuating means for said mechanism, manually-operable movement limiting means for said actuating means, an associated master key controlled by said limiting means adapted to start and stop said actuating means, means 40 for driving said actuating means, including a motor, a switch for the motor, and means for operating the switch to start and stop the motor actuated by movement of the limiting means.

50 9. In a ticket delivery machine, ticket issuing and severing mechanism, actuating means for said mechanism, manually-operable movement limiting means for said actuating means, an associated master key controlled by said limiting means adapted to start and stop said actuating means, means for locking the ticket issuing mechanism in inoperative position except when the ticket issuing mechanism is being operated by the 55 actuating means, and said severing mechanism including means for maintaining the shear blade closed when the ticket issuing mechanism is locked.

60 10. In a ticket delivery machine, ticket issuing and severing mechanism, actuating

means for said mechanism, manually-operable movement limiting means for said actuating means, an associated master key controlled by said limiting means adapted to start and stop said actuating means, said actuating means including means for moving the master key and its controlling movement limiting means to an inoperative position after each ticket issuing operation, and means for locking said movement limiting means in said inoperative position.

In testimony that I claim the above, I have hereunto subscribed my name.

LOUIS SCHER.
